UNITED STATES PATENT OFFICE.

JAMES T. COWLEY, OF NORTH SCITUATE, MASSACHUSETTS, ASSIGNOR TO THE LAMSON COMPANY, OF BOSTON, MASSACHUSETTS, A CORPORATION OF NEW JERSEY.

DISTRIBUTING SYSTEM.

1,170,048.

Specification of Letters Patent.

Patented Feb. 1, 1916.

Application filed March 19, 1914. Serial No. 825,735.

To all whom it may concern:

Be it known that I, JAMES T. COWLEY, a citizen of the United States, residing at North Scituate, in the county of Plymouth and State of Massachusetts, have invented 5 certain new and useful Improvements in Distributing Systems, of which the following is a specification.

This invention relates to despatch apparatus for merchandise, written messages, and the like, and more especially to what is known as a pick-up system.

Heretofore in pick-up apparatus the number of stations in a given line has been 15 necessarily limited by the impracticability of using selective switching or pick-up actuating apparatus in which any considerable number of gradations is provided, owing to the fact that the apparatus becomes too cumbersome or else too delicate in its adjustments.

One of the objects of the present system is to enable the provision of any desired number of stations, as for example, fifty or one 25 hundred or more, in a given line; all of these stations being served by a common apparatus.

A further object of the invention has been to provide such a combination of instruments in a system adapted to serve a large 30 number of stations, that any carrier or equivalent part of the conveying mechanism is adapted to serve any one of these stations; thus effecting a material saving of 35 time in the despatch of messages, parcels or the like, from one given point to another along the length of the system.

These and other objects of my invention will be hereinafter referred to and the novel 40 elements and combinations of means whereby said objects may be attained will be more particularly pointed out in the claims appended hereto.

In the drawings which form a part thereof 45 and in which like reference characters designate like parts in the respective views, I have shown, by way of exemplification, a preferred construction; but as I am aware of various changes and modifications which 50 may be made herein without departing from the spirit of my invention, I desire to be limited only by the scope of said claims, broadly considered in the light of my disclosure.

55 Referring to the drawings: Figure 1 is a

somewhat diagrammatic representation of a fragment of a system of the character in question. Fig. 1^a is a similar view of an other fragment of said system; which for present purposes may be regarded as a continuation of the part shown in Fig. 1. Fig. 2 is a wiring diagram of said system. Fig. 3 is a detail section taken on line III—III of Fig. 2. Fig. 4 is a similar section taken on line IV—IV of Fig. 2. Fig. 4^a is a section, similar to Fig. 4, of a sub-station push button box. Fig. 5 is a detail section taken on line V—V of Fig. 2. Fig. 6 is a detail elevation, drawn to an enlarged scale, of the cam-switch shown diagrammatically in Fig. 1^a at each of the several sub or clerk stations. Fig. 7 is a detail of a latch which forms a part of the switch mechanism. Fig. 8 is an end elevation of the apparatus shown in Fig. 6. Fig. 9 is a detail section taken on line IX—IX of Fig. 6. Fig. 10 is a rear elevation of the car shown in position upon the lower tracks in Fig. 8. Fig. 11 is a plan view of the message clamp which is carried by said car; the clamp being drawn 80 to a smaller scale than that to which it is shown in Fig. 8.

In Figs. 1 and 1^a, which may properly be considered together, the track or way along which the carriers travel comprises tracks 85 1, which in the present case are in vertical alignment, being looped at the respective ends of the line. The carriers, broadly designated 2, are propelled along this track by a cable 3 to which they are preferably permanently connected; the cable in turn being driven from one end of the line as shown to the left in Fig. 1^a. Here an electric motor 4 drives a belt 5 which passes around a pulley 6; and upon the shaft 7 of this pulley is a second pulley 8 with which the cable 3 is in engagement. The cable passes around a pulley 9 at its right hand end, as shown in Fig. 1, and this pulley is suitably geared, as by means of a belt 10 and pulleys 11, and 12, to an intermediate shaft 13. This shaft carries a pulley 14 which drives a belt 15, and the latter drives a pulley 16 mounted upon a shaft 17 which carries a drum 18, shown in detail in Fig. 3. 105 This drum is adapted to frictionally engage, and thereby rotate in the direction of the arrows shown thereupon, a disk 19 mounted upon a spindle 20 journaled in the respective extremities of a bifurcated arm 21. This 110

arm is made of electrically conductive material and is preferably resilient. Attached to the spindle 20, as indicated in Fig. 3, is a light spiral spring 22, the outer extremity 5 of which is connected to the disk 19. This disk is of conductive material and is in electrical communication via spindle 20 and arm 21 with a binding post 23 from which extends a wire 24. The periphery of disk 10 19 is practically encircled by the annular wall of a shallow cup 25 of insulating material; a gap 25' being left in this insulating material of sufficient width and depth to enable the edge of the disk 19 at this 15 point to contact with the conductive surface of the drum 18 when the disk 19 has been rotated counter-clockwise a determined distance, as viewed in Fig. 3, in the manner hereinafter described. Disk 19, it may be 20 here noted, is normally rotated clockwise by its spring 22 to the position in which it is shown in Fig. 3: a pin or stop 26 engaging the arm 21 and limiting the clock-wise rotation of the disk. Mounted upon the arm 25 21 is an armature 27 which is preferably insulated from said arm; said armature being adapted, when its electro-magnet 28 is energized, to draw the disk 19 inwardly toward the drum 18. This forces the insulating material 25 into engagement with 30 said drum and as the latter is rotated clock-wise, disk 19 will be rotated against the action of its spring 22, at a determined speed, until finally the gap 25' will be encountered 35 by drum 18 and the conductive surface of the latter will directly engage the exposed portion of the periphery of conductive disk 19, which will complete an electric circuit to be hereinafter more fully described.

40 The conductive shell 18 of the drum is preferably insulated from the core thereof, which is in engagement with shaft 17, by insulating material 29; and a resilient contact strip 30 lightly engages one end of the 45 drum as shown in Fig. 2. This strip extends up to a binding post 31 to which is attached a wire 32. The frame or casing 33 within which drum 18 is mounted may also conveniently be made of insulating material 50 and it preferably has mounted thereon a series of disks 19; the number of these corresponding to the number of sub-stations to be served. Each contact and timing disk 19 will hence have its own supporting arm 21 55 and magnet 28; drum 18 merely serving as a convenient source of power common to all of the timing disks and being further used as a contact member common to all of said disks, whereby to simplify the electrical 60 connections.

Referring again to Fig. 1, the central station or desk 34 is provided with a box 35 upon which are a series of buttons 36, one for each sub-station; these buttons being conveniently numbered or otherwise

marked in correspondence with the particular stations to which they respectively relate.

As shown in Fig. 4, each of these buttons is pivotally connected to a crank arm or lever 37 which is normally held in the position in which it is shown in said figure by a spring 38; the forward free extremity of said arm conveniently engaging the inner side of the cover of the box whereby to limit clockwise rotation of said arm. The horizontally extending portion of this crank arm carries a contact strip 39, insulated therefrom; said strip being adapted for engagement with contacts 40 insulatedly mounted upon the underside of the top of the box. These contacts are respectively in electrical connection with wires 41 and 42. The depending arm of the crank member carries an armature 43, preferably insulated therefrom, which armature is adapted to co-act with an electro-magnet 44, when the latter is energized, to hold the member 37 in position to close the circuit between wires 41 and 42. Each circuit maintaining magnet 44 may be mounted upon a bracket 45 secured to the inside of the casing or box 35, and the lower extremities of springs 38 may also be conveniently connected to this bracket. It will be understood, of course, that there is provided one magnet 44 and corresponding parts for each button 36 and as there are a series of wires 41 and 42, one of each for each station, for convenience these wires have been respectively designated 41, 41^a, 100 41^b, etc. and 42, 42^a, 42^b, etc. Each wire 41, 41^a, etc., extends to a corresponding electro-magnet 46, shown in detail in Fig. 5 as being mounted in a casing or box 47; there being of course one magnet 46 (comprising 105 two cores and their coils) for each sub-station. A wire 48 from each of these magnets extends down in said box to the lower end of a corresponding spring contact 49. Opposite each of these contacts 49 is a corresponding spring contact 49' which is in electrical connection with a wire 50, and since there are a series of these wires shown in the wiring diagram they have for convenience been designated 50, 50^a, 50^b, etc. 110 Below each magnet 46 is its armature 51 mounted upon an upright insulating support 52; said support also carrying hollow truncated conical contacts 53, and hence when the member 52 is driven upwardly by 115 pressure upon the button 54 which projects outwardly through the casing 47; the circuit which includes contacts 49 and 49' is closed, if it be not open at some other point along its course. There is provided in the 120 present system a button 54 for each sub-station and again for convenience these buttons have been designated 54, 54^a, 54^b, etc., and each of these buttons is preferably provided with a stem which extends upwardly 125 130

- therefrom through a guiding cup or shell 55; the upper extremity of each of said stems being rigidly connected to its corresponding element 52. Within each cup 55 is a light spring 56 which normally urges the corresponding button 54 and, of course, the corresponding contacts 53 to their respective lower positions in which they are shown in Fig. 5.
- 10 Referring to the sub-stations shown in Fig. 1^a it will be observed that each of these have been broadly designated with a letter corresponding to the electrical connections leading thereto; station *d* corresponding to button 54^a, *c* to 54^a, *b* to 54^b, *a* to 54^a, and station *o* to button 54. At each of these stations is a solenoid or some equivalent electromagnetic device 57 or, in correspondence with the system of nomenclature used 57^a, 57^b, etc. Each of these solenoids is connected by a lead 58, 58^a, 58^b, etc., with a wire 59 which constitutes, in the present case, the negative lead to the source of current, just as wire 32, previously referred to, constitutes the main positive lead. The second connection to each of these solenoids has been respectively designated, as per the foregoing 24, 24^a, 24^b, etc.; wire 24 having previously been referred to in the discussion of Fig. 3.
- 30 As best shown in Figs. 6 and 8 the core 60 of a solenoid 57 (57^a, 57^b, etc.,) carries upon its upper extremity an upstanding pin or extension 61 which is adapted for engagement with the free end of the spring contact 62.
- 35 So long as any given solenoid 57 is unenergized its solenoid will remain in its lower position and the contact 62 will resiliently engage a corresponding contact 63. A wire 64, 64^a, 64^b, etc., leads from each contact 62 to the corresponding wire 41, 41^a, 41^b, etc., and a second wire 65, 65^a, 65^b, etc., leads from each of the contacts 63 to the said negative lead 59. Connected to the lower extremity of each core 60 is a latch-link 66 which in turn is connected to a pivoted arm 67 which is preferably bifurcated, as shown in Fig. 9, for the reception of said link. Arm 67 may be conveniently mounted upon a shouldered stud 68 which is journaled in the offset end 69' of a fixed cam 69. The latter is preferably secured to one of the brackets 70 which support the tracks 1. The free end of arm 67 is preferably cammed, as at 67', and is adapted to be swung down into its dotted line position, shown in Fig. 6, when solenoid 57 is energized. I also prefer to bend the extremity of this cammed arm laterally, as at 67'' (see Fig. 9) and to connect a cord 71 thereto as indicated in Fig. 6. The arm 67 has therein a pin 72 to which is connected a spring 73, the other extremity of which is suitably attached to a corresponding pin 73' which projects upwardly from the inner side of a latch 74 so that spring 73 tends not only to elevate cam 67' but also, by reason of the weight of said movable cam, to move the latch into its latching position. The latch 74 is pivotally mounted upon the upper surface of member 69 adjacent the link 66; the pivot pin 75 of said latch extending vertically down into said member so that the latch swings in a horizontal plane. This latch is normally in engagement with or, in other words, is hooked under the surface 66' of the link 75 latch and affords a stop for downward movement of the core 60 and for the corresponding upward movement of the cam 67'. When solenoid 57 is energized and its core thereby lifted, link 66 is drawn upwardly 80 until the latch is snapped under surface 66'' of said link, which locks the core in its upper position and correspondingly the cam 67' in its lower or dotted line position. The latch 74 has a cam shaped arm 74' which 85 overhangs the surface of the fixed cam 69 and is adapted for engagement with and to be driven back by the head 76 of a stud upon which is mounted a roller 76' carried upon the upper extremity of a lever 77, one 90 of which levers is positioned upon each of the carriers 2, above referred to.
- Referring to Fig. 8, it will be seen that lever 77 is pivotally connected at 78 to an operating arm 79 which is in turn pivotally 95 mounted at 80 upon the carriage 81 of the carrier 2. A spring 82 which is connected to the upper arm of the lever 77 tends to hold said lever substantially at right angles to the arm 79; a stop 83 carried by the lever 100 77 engaging one side of said arm. Lever 77 is, however, adapted for movement independently of arm 79, to a limited extent; or in other words it may be moved into the dotted line position 77' shown in Fig. 8 105 without displacing said arm. At such time, however, a projection 84 disposed at the outer extremity of lever 77, is in engagement with the outer side of arm 79; so that thereafter if lever 77 be moved toward its 110 dotted line position 77'', arm 79 will be swung counter-clockwise together therewith, and since this arm is rigidly connected to the lower jaw 85 of the carrier clamp, said jaw will be swung down into its dotted line 115 position 85' shown in said figure, and will thereby release any article which may have been supported thereby. The upper jaw 86 of this clamp is preferably rigidly connected to the carriage 81. The clamp, *per se*, illustrated is one commonly in use in pick-up systems and is preferably made of bent wire; suitable ears or loops 87 and 88 being provided to retain, for example, a flat package or sheet of paper in place between the 120 clamp jaws; extensions 87 preventing displacement of the carried article in the direction of the length of the carriage and extension or loop 88 preventing displacement of said article laterally with respect to said 125
- 65 65

carriage. The cable 3 is preferably in sections which may have the ends thereof looped around eyelets 89; the latter in turn being attached to hooks or eyelets 90 which project rearwardly from a suitable extension 90' upon the back of the carriage 81. The cable is of course substantially taut. The upper and lower edges or surfaces of the carriage 81 may be grooved to adapt them for secure engagement with the tracks 1, as indicated in Figs. 8 and 10; and I prefer to form the carriage of superposed plates, the interior ones of which may be of fiber or the like to reduce noise. Upon the rear of the carriage is a sloping cam 91 connected to the carriage by screws or in any other suitable manner, said cam being adapted for engagement with the buttons 54, 54^a, etc., so that as each carriage is drawn along by the cable beneath these buttons, at the central station, they will be successively and gradually moved up into their casing 47. At each of the sub-stations and also at the central or main station or desk there is a shelf 92 into which articles to be conveyed may be placed by hand and from which said articles may be automatically removed by a passing carrier. There is also disposed at each station a receptacle 93 into which said articles may be deposited from the passing carriers; this receptacle in each case being preferably open on one side thereof to facilitate the removal of said articles therefrom. At each of the sub-stations there is also a casing 35' corresponding to the casing 35 and having therein a button 36' adapted to actuate a mechanism substantially identical with that shown in Fig. 4; the only difference being that wire 42 in Fig. 4 is omitted, the wire corresponding to 41 in Fig. 4 being designated 42. From each of the several magnets 44 in the casing 35 there extends downwardly a wire 94 which connects with the wire 32 previously referred to and each of these wires 94 may have a suitable resistance 95 interposed therein, as shown in Fig. 2. Correspondingly a wire 94' extends from each of the maintaining magnets 44 in casings 35', to the negative lead 59. It will of course be understood that since there is but a single button 36' at each sub-station there will be but a single magnet 44 in each casing 35', unless it be desired to extend the herein-described system so as to permit of inter-communication between sub-stations.

The operation of the system is as follows: Assuming that the operator stationed at the main or central desk wishes to despatch a message, such for example, as a telegram, to the operative at station *o*. The central station operator will thereupon press the button 36 marked O, which corresponds to station *o*, just as button A corresponds to station *a*, button B to station *b*, etc. This ac-

tion swings the lever 37 corresponding to the button depressed, counter-clockwise as viewed in Fig. 4, and closes circuit across contacts 40. No current flows however since the branch which includes wire 42 is open at station *o* and the branch which includes wire 41 is open at 49-49'. However, the first carrier which passes below the casing 47, will cause the successive elevation of each of the buttons 54, 54^a, etc., which will complete said circuit at 49-49'. Thereupon current flows from wire 32 through the wire 94 corresponding to button 36-O, thence through the corresponding magnet 44, energizing the same, and thereby retaining lever 37 in the position into which it has been moved. The current emerging from magnet 44 passes via wire 41 to the magnet 46 in circuit therewith, energizing it and thereby retaining contact 53 in its engagement with contacts 49-49' after button 54 has been freed by the onward movement of the carrier. The current then passes via wire 50 to the magnet 28 for station *o*, energizing it and thereby snapping the insulating strip 25 into engagement with drum 18. From magnet 28 the current flows through wire 97 to wire 64, through contacts 62 and 63 and wire 65 to the negative lead 59. There is of course a wire 97-97^a-97^b, etc., corresponding to each sub-station as, in like manner, there are pairs of contacts 62-63, which for convenience have been designated 62^a, 63^a; 62^b, 63^b; etc., at the respective stations. Continuing the description of the operation of the system, the actuation of the remaining buttons 54^a, 54^b, etc., will have no effect thereupon since in each of the circuits to which these buttons pertain there is still a break across the contacts 40 of each branch of each of said circuits owing to the fact that but one button 36 has been pressed at the main station. Every carrier approaching the buttons 54, etc., is an empty carrier, at least in the system given by way of exemplification, since a fixed cam 95 substantially similar to the cam 69, previously referred to, and having in this case, a permanently fixed or immovable portion 95' corresponding in shape to the cam 67', when the latter is in its depressed or dotted line position, serves to swing open the lower jaw 85 of each carrier in time to deposit its load in the receptacle 93 disposed at the central station, and to thereafter maintain jaw 85 in its open position until said jaw arrives substantially opposite the middle of shelf 92 at said station; whereupon the fixed cam permits the spring 96 upon the carrier to swing the lower jaw upwardly, its central or stem-like portion passing through the aperture 92' in the upper part of the shelf and the jaws 85 and 86 thereupon clamping or clasping the article to be conveyed therebetween. Preferably it

is while this picking up of the article from the shelf at the central station is taking place, that the buttons 54 are actuated by the cam 91 upon the back of the carrier carriage, so that the carrier is not only loaded automatically but that at substantially the same instant its destination, or rather the point or station for which its contents are destined, is definitely determined by the completion of the above circuit through wire 41, magnet 46, etc. When the insulating friction strip 25 corresponding to the given station *o* is thus moved into engagement with the conductive drum 18 by the energization of its magnet 28, this results in a determined, slow rotary movement being imparted to the disk 19 since drum 18 is normally always rotating at a constant speed in the direction of the arrows thereupon, and hence the spring 22 of such disk is gradually wound up. In the meanwhile, the carrier conveying the article despatched to station *o* is traversing the distance between the main station and said sub-station at a rate which, while it is greatly in excess of the speed of rotation of disk 19, is nevertheless directly proportioned thereto, and shortly before said carrier reaches said substation, disk 19 will have been rotated sufficiently to enable it to be snapped directly into engagement with the conductive drum 18 at the gap 25' in the insulating strip 25. This completes a circuit which controls the solenoid 57, since current will at such time be free to flow from positive lead 32 through contact strip 30, drum 18, disk 19, arm 21, wire 24, through the solenoid 57, and thence through wire 58 to the negative lead 59. This energization of solenoid 57, elevates its core and thereby swings down the corresponding movable cam 67' into a position where roller 76' will encounter it. As the carrier approaches the station at which it is to discharge, therefore, its said roller will ride up upon said movable cam, which will rotate arm 77 counter-clockwise until its extension 84 engages the operating arm 79 of said carrier; roller 76 in the meantime having ridden off of movable cam 67' on to fixed cam 69. The movable cam hence in effect acts as a bridge which is normally open but which may be moved down into position to cause a roller which would ordinarily not engage the fixed cam 69 to be moved up into engagement with said fixed cam.

As the carrier progresses its roller 76' rides on to the farther portion of cam 69 and is thereby driven still further rotarily counter-clockwise as viewed in Fig. 8, which forces open the clamp, and swings the lower jaw 85 thereof from positive lead 32 through contact strip 30, drum 18, disk 19, arm 21, wire 24, through the solenoid 57, and thence through wire 58 to the negative lead 59. This energization of solenoid 57 elevates its core and thereby swings down the corresponding movable cam 67' into a position where roller 76' will encounter it. As the carrier approaches the station at which it is to discharge, therefore, its said roller will ride up upon said movable cam, which will rotate arm 77 counter-clockwise until its extension 84 engages the operating arm 79 of said carrier; roller 76 in the meantime having ridden off of movable cam 67' on to fixed cam 69. The movable cam hence in effect acts as a bridge which is normally open but which may be moved down into position to cause a roller which would ordinarily not engage the fixed cam 69 to be moved up into engagement with said fixed cam.

As the carrier progresses its roller 76' rides on to the farther portion of cam 69 and is thereby driven still further rotarily counter-clockwise as viewed in Fig. 8, which forces open the clamp, and swings the lower jaw 85 thereof from positive lead 32 through contact strip 30, drum 18, disk 19, arm 21, wire 24, through the solenoid 57, and thence through wire 58 to the negative lead 59. This energization of solenoid 57 elevates its core and thereby swings down the corresponding movable cam 67' into a position where roller 76' will encounter it. As the carrier approaches the station at which it is to discharge, therefore, its said roller will ride up upon said movable cam, which will rotate arm 77 counter-clockwise until its extension 84 engages the operating arm 79 of said carrier; roller 76 in the meantime having ridden off of movable cam 67' on to fixed cam 69. The movable cam hence in effect acts as a bridge which is normally open but which may be moved down into position to cause a roller which would ordinarily not engage the fixed cam 69 to be moved up into engagement with said fixed cam.

As the carrier progresses its roller 76' rides on to the farther portion of cam 69 and is thereby driven still further rotarily counter-clockwise as viewed in Fig. 8, which forces open the clamp, and swings the lower jaw 85 thereof from positive lead 32 through contact strip 30, drum 18, disk 19, arm 21, wire 24, through the solenoid 57, and thence through wire 58 to the negative lead 59. This energization of solenoid 57 elevates its core and thereby swings down the corresponding movable cam 67' into a position where roller 76' will encounter it. As the carrier approaches the station at which it is to discharge, therefore, its said roller will ride up upon said movable cam, which will rotate arm 77 counter-clockwise until its extension 84 engages the operating arm 79 of said carrier; roller 76 in the meantime having ridden off of movable cam 67' on to fixed cam 69. The movable cam hence in effect acts as a bridge which is normally open but which may be moved down into position to cause a roller which would ordinarily not engage the fixed cam 69 to be moved up into engagement with said fixed cam.

As the carrier progresses its roller 76' rides on to the farther portion of cam 69 and is thereby driven still further rotarily counter-clockwise as viewed in Fig. 8, which forces open the clamp, and swings the lower jaw 85 thereof from positive lead 32 through contact strip 30, drum 18, disk 19, arm 21, wire 24, through the solenoid 57, and thence through wire 58 to the negative lead 59. This energization of solenoid 57 elevates its core and thereby swings down the corresponding movable cam 67' into a position where roller 76' will encounter it. As the carrier approaches the station at which it is to discharge, therefore, its said roller will ride up upon said movable cam, which will rotate arm 77 counter-clockwise until its extension 84 engages the operating arm 79 of said carrier; roller 76 in the meantime having ridden off of movable cam 67' on to fixed cam 69. The movable cam hence in effect acts as a bridge which is normally open but which may be moved down into position to cause a roller which would ordinarily not engage the fixed cam 69 to be moved up into engagement with said fixed cam.

As the carrier progresses its roller 76' rides on to the farther portion of cam 69 and is thereby driven still further rotarily counter-clockwise as viewed in Fig. 8, which forces open the clamp, and swings the lower jaw 85 thereof from positive lead 32 through contact strip 30, drum 18, disk 19, arm 21, wire 24, through the solenoid 57, and thence through wire 58 to the negative lead 59. This energization of solenoid 57 elevates its core and thereby swings down the corresponding movable cam 67' into a position where roller 76' will encounter it. As the carrier approaches the station at which it is to discharge, therefore, its said roller will ride up upon said movable cam, which will rotate arm 77 counter-clockwise until its extension 84 engages the operating arm 79 of said carrier; roller 76 in the meantime having ridden off of movable cam 67' on to fixed cam 69. The movable cam hence in effect acts as a bridge which is normally open but which may be moved down into position to cause a roller which would ordinarily not engage the fixed cam 69 to be moved up into engagement with said fixed cam.

cams without hindrance and therefore a given carrier will only discharge at a determined station when said movable cam has been moved into the path of its roller by means of the electrical connections and electrically operated instrumentalities above described. It is this particular feature which eliminates the necessity for very close adjustments if any considerable number of stations be employed in the system, the disposition of the gap 25' in the insulating material 25, and the speed of rotation of the disk 19, determining the distance which a given loaded carrier must traverse before the next cam switch which it must pass will be lowered or otherwise moved into the path of the roller or some corresponding part of the load releasing mechanism. In the system shown the gap 25' in the insulating material adjacent each timing contact disk 19 will be progressively farther and farther away from the stop 26, measuring angularly and clockwise; so that while contact between disk 19 and drum 18 may be effected after a lapse of, let us say, 10 seconds, for discharging an article at station *a*, a similar contact would not be made for, let us say, 15 seconds after the loading of a carrier which is to be discharged at station *a*, and correspondingly a like contact for station *b* may be made, let us say, 20 seconds after the carrier is loaded at the main station, when said carrier is to discharge at station *b*, and so on.

If an operative at a sub-station desires to despatch a message or other article to the chief operator at the central station it is merely sufficient to place the article to be despatched in the receiving shelf 92 of said station and, as the first approaching empty carried nears said sub-station, to pull the corresponding cord 71, which latches down the cam 67' of said station so that the approaching unloaded carrier will have its pick-up mechanism operated by the riding up of its roller 76' upon the cam 67' and thereafter by the further actuation of said roller by fixed cam 69, in substantially the manner above described. Thereafter the now loaded carrier will traverse the track or way toward the pulley 8 and will pass there-around returning to the central station along the upper side of the track and ultimately depositing its load in the receptacle 93 at the central station in the manner indicated. Obviously, the sub-station operative should not thus actuate his pull-cord 71 if an approaching carrier be already loaded. It at times happens, owing to the disposition of the tracks through walls in a building or for other cause, that the condition of approaching carriers cannot be perceived by the sub-station operative. In such case he may use the button 36' at his station in lieu of pulling cord 71 and the system will then operate as follows: Assuming that the sub-

station operator is at station *d*. Pressure upon the button 36' of this station will cause current to flow from wire 32 through wire 94 and magnet 44 at the central desk corresponding to button D, wire 42^d, contacts 39 and 40, magnet 44 at sub-station *d* and wire 94' of said sub-station to the negative lead 59; thus energizing not only the magnet 44 at the particular sub-station in question, which thereupon maintains the circuit closed across contacts 40, but further energizing the said magnet 44 corresponding to button D at the main desk, and this latter causes the retraction of button D partly within the casing 35; notifying the operator at the central station that the operative at station *d* desires to despatch a message. Closure of the circuit across contacts 40 of button D will now have the same effect upon the system as pressure upon the button D by the central station operator would have. The first car to pass the central station after this will be unloaded and will thereafter travel on toward station *d* either with or without a load which it may pick up at the central station until it reaches sub-station *d*, whereupon since the friction insulating strip 25 corresponding to station *d* will have been engaged by drum 18 and rotated thereby until its gap 25' shall have been snapped into engagement with said drum, (this movement of said strip 25 beginning at the instant that the said carrier passes the central desk and the said contact between disk 19 and drum 18 having been effected shortly before said carrier reached the bridge cam 67' of station *d*); the roller 76' of said carrier will ride up upon this movable cam and the fixed cam 69 will then open the clamp of the carrier depositing therefrom any message or article which it may have carried from the central desk, but in any case not closing until the said movable jaw is in position to pick up the article or message which the sub-station operative at *d* had previously deposited in his sending shelf 92. In other words whenever a bridge cam 67' is depressed and the roller of a carrier thereafter rides up upon said cam and from the latter on to the fixed cam 69, to open the clamp of said carrier and deposit articles therefrom into receptacle 93 of said station, said clamp will in no case again close until it reaches a position where it will unfailingly pick up any article adapted to be carried thereby which may be reposing in the corresponding shelf 92; fixed cam 69 being sufficiently extended to accomplish this action, as indicated in Fig. 1^a.

Ordinarily in a system actively in use it will not be necessary for the sub-station operatives to actuate either the buttons 36' or the cords 71; since the central station operator will be sending messages or articles from time to time to each of the sub-stations and

if before the arrival of the loaded carrier at any given sub-station, the operative thereat has placed the matter or articles to be returned to the central desk in his sending shelf, the said carrier will, for reasons above indicated, in such case perform the dual function of not only delivering the message or article to such station but of immediately thereafter picking up the message or article to be despatched therefrom, and this without further attention on the part of the operative. It will, hence, be seen that my system is practically completely automatic and one of its principal advantages is that it 15 may be extended indefinitely so that if desired a hundred or more stations may be conveniently served by it, a thing which, to the best of my knowledge, has heretofore been found to be utterly impracticable with 20 known apparatus.

Having thus described my invention what I claim is:—

1. A delivery system for parcels, messages and like articles, which comprises a way having therealong a plurality of stations and automatic mechanism for conveying an article from one of said stations to and unloading said article at any other desired one of said stations, said mechanism including a plurality of timing elements, one for each of said other stations, each of said elements being adapted to time differently from the others of said elements to determine by the lapse of different periods of time the station at which said article is to be unloaded, said mechanism also including time element controlled means for unloading said article at said desired station after the lapse of the particular period 40 of time allotted by the timing element corresponding to said last mentioned station.
2. A delivery system for parcels, messages and like articles, which comprises a way having therealong a plurality of stations, automatic mechanism for conveying an article from one of said stations to and unloading said article at any other desired one of said stations, said mechanism including a plurality of timing elements, one for each of said other stations, each of said elements being adapted to time differently from the others of said elements to determine by the lapse of different periods of time the station at which said article is to be unloaded, said mechanism also including time element controlled means for unloading said article at said desired station after the lapse of the particular period of time allotted by the timing element corresponding to said desired station, and means, controlling parts of which are located at the station from which said article is despatched, for determining which of said timing elements is to become operative.
3. A delivery system for parcels, mes-

sages and like articles, which comprises a way having therealong a plurality of stations, automatic mechanism for conveying an article from one of said stations to and unloading said article at any other desired one of said stations, said mechanism including a plurality of timing elements, one for each of said other stations, each of said elements being adapted to time differently from the others of said elements to determine by the lapse of different periods of time the station at which said article is to be unloaded, said mechanism also including time element controlled means for unloading said article at said desired station after the lapse of the particular period of time allotted by the timing element corresponding to said desired station, and means for determining which of said timing elements is to become operative, whereby to predetermine the station at which said article will be discharged.

4. A delivery system for parcels, messages and like articles, which comprises a way having therealong a plurality of stations, automatic means for starting an article at one of said stations and conveying said article along said way past at least a second of said stations to another and predetermined station, and means including a timing mechanism, separate from the means for conveying said article for automatically unloading said article only at said predetermined station.

5. A delivery system for parcels, messages and like articles which comprises a way having therealong a plurality of stations, automatic means for conveying an article from one of said stations at which said article is despatched, past a second of said stations to another and predetermined station, means including variably acting timing mechanism for automatically unloading said article only at said predetermined station, said timing mechanism being separate and distinct from said conveying means, and means for setting said timing mechanism to time a determined period allotted for the transmission of an article from said despatching station substantially to said predetermined station.

6. A delivery system for parcels, messages and like articles which comprises a way having therealong a plurality of stations, automatic means for conveying an article from one of said stations at which said article is despatched, past a second of said stations to another and predetermined station, means including variably acting timing mechanism for automatically unloading said article only at said predetermined station, said timing mechanism being separate and distinct from said conveying means, and electrical means for setting said timing mechanism to time a determined

period allotted for the transmission of an article from said despatching station substantially to said predetermined station.

7. A delivery system for parcels, messages and like articles which comprises a way having therealong a plurality of stations, automatic means for conveying an article from one of said stations at which said article is despatched, past a second of said stations to another and predetermined station, means including a timing mechanism, operating continuously during the time of transit of the article to be conveyed, for automatically stopping said conveyance of said article at said predetermined station and means to thus continuously actuate said timing mechanism, and means for controlling said timing mechanism from said station from which said article is despatched.

8. A delivery system for parcels, messages and like articles which comprises a way having therealong a plurality of stations, automatic means for conveying an article from one of said stations at which said article is despatched, past a second of said stations to another and predetermined station, means including a timing mechanism operating continuously during the given period of time which it determines for automatically stopping said conveyance of said article at said predetermined station, and electrical means for controlling said timing mechanism from said station from which said article is despatched.

9. A delivery system for parcels, messages and like articles which comprises a way having therealong a plurality of stations, a carrier to travel along said way, means to propel said carrier along said way, and automatic means for unloading an article from said carrier at a predetermined one of said stations, said means including a time-element mechanism adapted to be set to run substantially coincidentally with the travel of said carrier while the latter is traversing said way between the one of said stations at which said article was despatched and said predetermined station and means to continuously operate said time-element mechanism during the time that it is thus set to run.

10. A delivery system for parcels, messages and like articles which comprises a way having therealong a plurality of stations, a carrier to travel along said way, means to propel said carrier along said way, automatic means for unloading an article from said carrier at a predetermined one of said stations, said means including a time-element mechanism adapted to be set to run continuously substantially coincidentally with the travel of said carrier while the latter is traversing said way between the one of said stations at which said article was despatched and said predetermined station,

and means to set said mechanism to time said travel of said carrier and to thereby predetermine the station at which said carrier is to discharge.

11. A delivery system for parcels, messages and like articles which comprises a way having therealong a plurality of stations, a carrier to travel along said way, means to propel said carrier along said way, automatic means for unloading an article from said carrier at a predetermined one of said stations, said means including a time-element mechanism adapted to be set to run substantially coincidentally with the travel of said carrier while the latter is traversing said way between the one of said stations at which said article was despatched and said predetermined station, means to set said mechanism to time said travel of said carrier and to thereby predetermine the station at which said carrier is to discharge, and means to automatically return said timing mechanism to its normal position after it has timed said carrier in manner aforesaid.

12. A delivery system for parcels, messages and like articles, which comprises a way having a station from which articles are despatched, a carrier to travel along said way separate from the carrier, means to time the progress of said carrier along said way from said station to a point at which said carrier is to unload, means to automatically start said last mentioned means to time said carrier only after said carrier has passed a determined point in said way, and means, controlled by said timing means, for unloading said carrier at said first mentioned point.

13. A delivery system for parcels, messages and like articles, which comprises a way having a station from which articles are despatched, a carrier to travel along said way, means to load said carrier at said station, means, separate from the carrier, to time the progress of said carrier along said way from said station to a point at which said carrier is to unload, means to automatically start said last mentioned means to time said carrier only after said carrier has passed a determined point in said way, and means, controlled by said timing means, for unloading said carrier at said first mentioned point.

14. A delivery system for parcels, messages and like articles, which comprises a way having a station from which articles are despatched, a carrier to travel along said way, automatic means to load said carrier at said station, timing means adapted when once set in operation to of itself time the progress of said carrier along said way from said station to a point at which said carrier is to unload, means to automatically start said last mentioned means to time said carrier only after said carrier has passed a

determined point in said way, and means, controlled by said timing means, for unloading said carrier at said first mentioned point.

5 15. A pick-up system for parcels, messages and like articles, which comprises a track having therealong a plurality of stations, a despatching shelf at at least one of said stations, a pick-up carrier to travel 10 along said track from said despatching shelf toward said other stations, means to propel said carrier along said track, means to actuate parts of said carrier to pick-up an article upon said shelf as said carrier 15 passes the same, and means to actuate parts of said carrier to deposit said article at any predetermined one of said other stations, said last mentioned means including an operating part adjacent said predetermined 20 station and normally out of the path of said carrier, a time-element mechanism adapted to be set to run for a determined period in substantial synchronism with the period during which said carrier is traveling from 25 said shelf toward said operating part and means controlled by said time-element mechanism for placing said operating part in the path of said carrier.

16. A pick-up system for parcels, messages and like articles, which comprises a track having therealong a plurality of stations, a despatching shelf at at least one of said stations, a pick-up carrier to travel along said track from said despatching shelf 30 toward said other stations, means to propel said carrier along said track, means to actuate parts of said carrier to pick-up an article upon said shelf as said carrier passes the same, means to actuate parts of said carrier 35 to deposit said article at any predetermined one of said other stations, said last mentioned means including an operating part adjacent said predetermined station and normally out of the path of said carrier, a 40 time-element mechanism adapted to be set to run for a determined period in substantial synchronism with the period during which said carrier is traveling from said shelf toward said operating part and means 45 controlled by said time-element mechanism for placing said operating part in the path of said carrier.

17. A pick-up system for parcels, messages and like articles, which comprises a 50 closed track having therealong a plurality of stations, a despatching shelf at at least one of said stations, a pick-up carrier to travel along said track from said despatching shelf toward said other stations and 55 then back toward said shelf, a cable to propel said carrier along said track, means to actuate parts of said carrier to pick-up an article upon said shelf as said carrier passes the same, and means to actuate parts of said carrier to deposit said article at any pre- 60

determined one of said other stations, said last mentioned means including an operating part adjacent said predetermined station and normally out of the path of said carrier, a time-element mechanism adapted 70 to be set to run for a determined period in substantial synchronism with the period during which said carrier is traveling from said shelf toward said operating part and means controlled by said time-element 75 mechanism for placing said operating part in the path of said carrier.

18. A delivery system for parcels, messages and like articles, which comprises a track, a carrier to travel along said track, 80 means to load said carrier at one point in said track, and means to unload said carrier at a second point in said track, said last mentioned means including a carrier-unloading actuating member mounted to move 85 with said carrier, an unloading cam substantially at said second point and adapted to operate said actuating member, said unloading cam being normally out of the path of said member, and means, controlled from 90 said first point, for effecting an engagement between said actuating member and said unloading cam.

19. A delivery system for parcels, messages and like articles, which comprises a 95 track, a carrier to travel along said track, means to load said carrier at one point in said track, and means to unload said carrier at a second point in said track, said last mentioned means including a carrier-unloading 100 actuating member mounted to move with said carrier, an unloading cam substantially at said second point and adapted to operate said actuating member, said unloading cam being normally out of the path of said member, and means for effecting a relative movement between said unloading cam and said actuating member to permit of engagement therebetween when said member has traveled substantially up to said cam in 110 company with said carrier.

20. A delivery system for parcels, messages and like articles, which comprises a track, a carrier to travel loaded along said track from a given point therein, and means 115 to unload said carrier at a second point in said track, said means comprising a carrier-unloading actuating member mounted to move with said carrier, an unloading cam substantially at said second point and 120 adapted to operate said actuating member, said unloading cam being normally out of the path of said member, and means, controlled from said first point, for effecting an engagement between said actuating member and said unloading cam.

21. A delivery system for parcels, messages and like articles, which comprises a track, a carrier to travel loaded along said track from a given point therein, and means 125

to unload said carrier at any predetermined one of a plurality of points relatively remote from said first point, said means including a part at each of said plurality of points which is normally inoperative and unadapted to affect the carrier when the latter is passing thereby, means to control said parts, means to set said controlling means to effect an actuation of a predetermined one of said parts, and means to jointly control the operation of said last mentioned means by the operative at, and by the passage of said car past, said first mentioned point.

22. A delivery system for parcels, messages and like articles, which comprises a track, a carrier to travel loaded along said track from a given point therein, and means to unload said carrier at any predetermined one of a plurality of points relatively remote from said first point, said means including a part at each of said plurality of points which is normally inoperative and unadapted to affect the carrier when the latter is passing thereby, means to control said parts, means to set said controlling means to effect an actuation of a predetermined one of said parts, and means to jointly and co-operatively control the operation of said last mentioned means manually and by the arrival of said car at a given point in said track.

23. A delivery system for parcels, messages and like articles, which comprises a track, a plurality of carriers to travel along said track, means to unload any one of said carriers at any one of a plurality of stations along said track, and conjointly acting means to control said unloading means including a device adapted to be manually set to ultimately cause the unloading of a carrier at a given one of said stations and co-acting mechanism controlled by the first of said carriers to pass a given point in said track, said device and mechanism having operative connections therebetween whereby while the setting of said device predetermines the station at which a carrier is to unload, the passage of a carrier past said given point is requisite to render operative said means to control said unloading means.

24. A delivery system for parcels, messages and like articles, which comprises a track, a plurality of carriers to travel along said track, means to unload any one of said carriers at any one of a plurality of stations along said track, and conjointly acting means to control said unloading means including a device adapted to be manually set to ultimately cause the unloading of a carrier at a given one of said stations, a second device controlled by the first of said carriers to pass a given point in said track, a time element mechanism jointly controlled by said first and second devices and operative

connections between said devices and time element mechanism whereby while the setting of said first device predetermines the station at which a carrier is to unload, the passage of a carrier past said given point is requisite to render operative said time element mechanism to time said last mentioned carrier, said carrier unloading means including an operating part therefor which is controlled by said time element mechanism after the latter has operated for a determined period subsequent to the passage of said carrier past said given point.

25. A delivery system comprising a way, a carrier to travel along said way, said way having therealong a station at which a load is emplaced on said carrier and a plurality of other stations at which said load may be deposited, a carrier unloading operating part relatively adjacent each of said other stations, said parts being normally out of the path of said carrier, means to project any one of said operating parts into the path of said carrier after the lapse of a substantially determined period of time running from the despatching of the load, and means to predetermine which of said parts shall be so projected.

26. A delivery system comprising a way, a plurality of carriers to travel along said way, said way having therealong a station at which a load is emplaced on any one of said carriers and a plurality of other stations at each of which said load may be deposited, carrier unloading means, a part at least of which travels with each of said carriers, and controlling and timing mechanism for said parts, adapted when once set in operation to of itself cause the actuation of said part for a predetermined one of said carriers only at, a substantially determined period of time after said carrier has been loaded at said first mentioned station.

27. A delivery system comprising a way, a plurality of carriers to travel along said way, said way having therealong a station at which a load is emplaced on any one of said carriers and a plurality of other stations at each of which said load may be deposited, carrier unloading means, a part at least of which travels with each of said carriers, controlling mechanism for said parts to only actuate the said part for a predetermined one of said carriers, a substantially determined period of time after said carrier has been loaded at said first mentioned station, and means for variably determining said period of time in accordance with the station for which said load is destined.

28. A delivery system comprising a way, a plurality of carriers to travel along said way, said way having therealong a station at which a load is emplaced on any one of said carriers and a plurality of other sta-

- tions at each of which said load may be deposited, carrier unloading means, and controlling and timing mechanism for said unloading means adapted when once set in operation to of itself cause the actuation of the latter for a predetermined one of said carriers, a substantially predetermined period of time after said carrier has been loaded at said first mentioned station.
- 10 29. A delivery system comprising a way, a plurality of carriers to travel along said way, said way having therealong a station at which a load is emplaced on any one of said carriers and a plurality of other stations at each of which said load may be deposited, carrier unloading means, controlling and timing mechanism for said unloading means adapted when once set in operation to of itself cause the actuation of the latter for a predetermined one of said carriers, a substantially predetermined period of time after said carrier has been loaded at said first mentioned station, and means for variably determining said period of time in accordance with the station for which said load is destined.
- 30 30. A delivery system comprising a way, a plurality of carriers to travel along said way, said way having therealong a station at which a load is emplaced on any one of said carriers and a plurality of other stations at each of which said load may be deposited, carrier unloading means, controlling and timing mechanism for said unloading means, adapted when once set in operation to of itself cause the actuation of the latter for a predetermined one of said carriers, a substantially predetermined period of time after said carrier has been loaded at said first mentioned station, and means at the loading station for variably determining said period of time in accordance with the station for which said load is destined.
- 45 31. A pick-up carrier system comprising a way having therealong a plurality of stations, carriers to travel along said way and having parts adapted to pick-up a load at any predetermined one of said stations, and means for predetermining the station at which said load is to be picked up, said means including a device at each of said stations for actuating the pick-up part of any one of said carriers, said devices being normally out of the path of said carriers and elements also normally out of the path of said carriers and each adapted when in said path to effect an engagement between the pick-up part of any carrier which passes said element and the next pick-up actuating device which said carrier passes.
- 55 32. A pick-up carrier system comprising a way having therealong a plurality of stations, carriers to travel along said way and having parts adapted to pick-up a load at
- any predetermined one of said stations, and means for predetermining the station at which said load is to be picked up, said means including a device at each of said stations for actuating a pick-up part of any one of said carriers, said devices being normally out of the path of said carriers; elements also normally out of the path of said carriers and each adapted when in said path to effect an engagement between the pick-up part of any carrier which passes said element and the next pick-up actuating device which said carrier passes, said devices being normally out of the path of said carriers; elements also normally out of the path of said carriers and each adapted when in said path to effect an engagement between the pick-up part of any carrier which passes said element and the next pick-up actuating device which said carrier passes, and means for moving any desired one of said elements into the path of the carriers to predetermine the station at which the load is to be picked up, and electrically controlled means for predetermining which of said carriers is to pick up the load at said predetermined station.
- 65 33. A pick-up carrier system comprising a way having therealong a plurality of stations, carriers to travel along said way and having parts adapted to pick-up a load at any predetermined one of said stations, and means for predetermining the station at which said load is to be picked up, said means including a device at each of said stations for actuating a pick-up part of any one of said carriers, said devices being normally out of the path of said carriers; elements also normally out of the path of said carriers and each adapted when in said path to effect an engagement between the pick-up part of any carrier which passes said element and the next pick-up actuating device which said carrier passes, and means, at a point remote from the station at which the load is to be picked up, for controlling the movement into the path of the carriers of the one of said elements at the station at which the load is to be picked up.
- 75 34. A pick-up carrier system comprising a way having therealong a plurality of stations, carriers to travel along said way and having parts adapted to pick up a load at any predetermined one of said stations, and means for predetermining the station at which said load is to be picked up, said means including a device at each of said stations for actuating a pick-up part of any one of said carriers, said devices being normally out of the path of said carriers; elements also normally out of the path of said carriers and each adapted when in said path to effect an engagement between the pick-up part of any carrier which passes said element and the next pick-up actuating device which said carrier passes, means for moving any desired one of said elements into the path of the carriers to predetermine the station at which the load is to be picked up, and electrically controlled means for predetermining which of said carriers is to pick up the load at said predetermined station.
- 85 35. A pick-up carrier system comprising

a way having therealong a plurality of stations, carriers to travel along said way and having parts adapted to pick-up a load at any predetermined one of said stations, and means for predetermining the station at which said load is to be picked up, said means including a device at each of said stations for actuating a pick-up part of any one of said carriers, said devices being normally out of the path of said carriers, elements also normally out of the path of said carriers and each adapted when in said path to effect an engagement between the pick-up part of any carrier which passes said element and the next pick-up actuating device which said carrier passes, means for moving any desired one of said elements into the path of the carriers to predetermine the station at which the load is to be picked up, and means for predetermining which of said carriers is to pick up the load at said predetermined station.

36. A pick-up carrier system comprising a way having therealong a plurality of stations, carriers to travel along said way and having parts adapted to pick-up a load at any predetermined one of said stations, and means for predetermining the station at which said load is to be picked up, said means including a device at each of said stations for actuating a pick-up part of any one of said carriers, said devices being normally out of the path of said carriers, elements also normally out of the path of said carriers and each adapted when in said path to effect an engagement between the pick-up part of any carrier which passes said element and the next pick-up actuating device which said carrier passes, and means, at a point remote from the station at which the load is to be picked up, for controlling the movement into the path of the carriers of the one of said elements at the station at which the load is to be picked up and for determining which of said carriers shall pick up said load.

37. A delivery system comprising a way having stations therealong, a plurality of carriers to travel along said way, means for automatically loading said carriers, and means at one of said stations for determining which of said carriers shall be automatically loaded by said loading means at another of said stations.

38. A delivery system comprising a way having stations therealong, a plurality of carriers to travel along said way, means for automatically loading said carriers, means at one of said stations for determining which of said carriers shall be automatically loaded by said loading means at another of said stations, and means for automatically unloading said loaded carrier at the station from which the said determination was made.

39. A pick up and delivery system comprising a substantially horizontal way, a plurality of invariably identical pick-up carriers to travel along said way, said carriers each having means for picking up and thereafter supporting a load to be carried, means to propel said carriers, a central station and sub-stations along said way, means at said central station for actuating the pick-up means upon any one of said carriers, as the latter moves horizontally therewith, for emplacing upon said carrier a load destined for any predetermined one of said sub-stations, and means for automatically unloading said carrier at said predetermined sub-station.

40. A delivery system comprising a way, a plurality of identical carriers to travel along said way, means to propel said carriers, a central station and sub-stations along said way, means at said central station for despatching upon any one of said carriers a load destined for any predetermined one of said sub-stations, means for automatically unloading said carrier at said predetermined sub-station, including a normally inoperative controlling part at each of said sub-stations, and means at said central station for rendering operative any desired one of said controlling parts.

41. A delivery system comprising a way, a plurality of identical carriers to travel along said way, means to propel said carriers, a central station and sub-stations along said way, means at said central station for despatching upon any one of said carriers a load destined for any predetermined one of said sub-stations, means for automatically unloading said carrier at said predetermined sub-station, including a normally inoperative controlling part at each of said sub-stations, and means at said central station for rendering operative any desired one of said controlling parts only after the lapse of a determined period of time running from the despatch of said load.

42. A pick-up system comprising a track, a plurality of pick-up carriers to travel on said track, a cable to propel said carriers, a central station and sub-stations along said track, means at said central station for loading the next of said carriers which approaches said central station when a load is to be despatched, a contact making device comprising sets of contacts and circuit maintaining means therefor respectively corresponding to the several sub-stations, a station predetermining device comprising sets of contacts and circuit maintaining means therefor, respectively corresponding to the several sub-stations, a fixed cam at each of said sub-stations to unload any given carrier the pick-up mechanism of which has been arranged to co-act with said fixed cam, a bridge-cam at each of said sub-

stations adapted when operatively disposed to arrange the carrier mechanism to co-act with the corresponding fixed cam, electro-magnetic means to actuate said bridge cams, 5 an electrically controlled circuit making time element device for each sub-station, and electrical connections between the respective sets of contacts and maintaining means aforesaid, said time element devices 10 and said electro-magnetic means, whereby when said station predetermining device has been set to cause the delivery of a load at a given sub-station, and after the carrier which is to convey said load has reached 15 said contact making device, the time element device for said given sub-station will start to time said carrier and after the lapse of a determined period of time sufficient to enable said carrier to have passed the sub- 20 station next preceding the determined one, will energize the electro-magnetic device corresponding to said determined sub-station to thereby operatively dispose said bridge cam to cause the carrier pick-up 25 mechanism to co-act with the fixed cam at said sub-station and unload said carrier.

43. A pick-up system comprising a track, a plurality of pick-up carriers each having an actuating part for unloading said carriers, a plurality of stations along said track each having a fixed unloading cam normally out of the path of said actuating parts, a movable bridge for each of said fixed cams adapted when in one position to 30 guide the actuating part of a carrier approaching the corresponding station, onto the corresponding unloading cam, and means, controlled from a remote point, for moving the said bridge of any of said stations out of a normal position into the position aforesaid.

44. A pick-up system comprising a track, a plurality of pick-up carriers each having an actuating part for unloading said carriers, a plurality of stations along said track each having a fixed unloading cam normally out of the path of said actuating parts, a movable bridge for each of said fixed cams adapted when in one position to guide the 45 actuating part of a carrier approaching the corresponding station, onto the corresponding unloading cam, and means for moving the said bridge of any of said stations out of a normal position into the position aforesaid.

45. A pick-up system comprising a track, a plurality of pick-up carriers each having an actuating part for unloading said carriers, a plurality of stations along said track each having an unloading cam normally out of the path of said actuating parts, a movable bridge for each of said cams adapted when in one position to guide the actuating 50 part of a carrier approaching the corresponding station, onto the corresponding

unloading cam, and means, for moving the said bridge of any of said stations out of a normal position into the position aforesaid.

46. A delivery system for parcels, messages and like articles which comprises a 70 way having therealong a plurality of stations, automatic means for conveying an article from one of said stations at which said article is despatched, past a second of said stations to another and predetermined station, and means including a timing mechanism, an electro-magnetic device at said predetermined station and electrical connections between said timing mechanism and said device for automatically stopping said 75 conveyance of said article at said predetermined station.

47. A pick-up system for parcels, messages and like articles, which comprises a track having therealong a plurality of stations, means for holding an article to be despatched at at least one of said stations, a pick up carrier to travel along said track from said holding means toward said other stations, means to propel said carrier along 85 said track, means to actuate parts of said carrier to pick up an article from said holding means as said carrier passes the same, and means to actuate parts of said carrier to deposit said article at any predetermined one 90 of said other stations, said last mentioned means including an operating part adjacent said predetermined station, which part is normally inoperative, a time-element mechanism adapted to be set to run for a determined period in substantial synchronism 95 with the period during which said carrier is traveling from said holding means toward said operating part and means controlled by said time-element mechanism for rendering 100 operative said operating part as said carrier approaches the same.

48. A pick-up system for parcels, messages and like articles, which comprises a track having therealong a plurality of stations, means for holding an article to be despatched at at least one of said stations, a pick up carrier to travel along said track from said holding means toward said other stations, means to propel said carrier along 110 said track, means to actuate parts of said carrier to pick up an article from said holding means as said carrier passes the same, and means to actuate parts of said carrier to deposit said article at any predetermined 115 one of said other stations, said last mentioned means including an electrically conductive operating part, adjacent said predetermined station, which part is normally inoperative, a time-element mechanism 120 adapted to be set to run for a determined period in substantial synchronism with the period during which said carrier is traveling from said holding means toward said operating part and means controlled by said 125 123

time-element mechanism for electrically energizing said operative part.

49. A delivery system for parcels, messages and like articles, which comprises a track, a carrier to travel loaded along said track from a given point therein, and means to unload said carrier at any predetermined one of a plurality of points relatively remote from said first point, said means including a part at each of said plurality of points which is normally inoperative and unadapted to affect the carrier when the latter is passing thereby, time-element means to control said parts, constantly operative power supplying connections between said carrier and a part of said time element means, and means to set said controlling means to render operative a determined one of said parts.

50. A delivery system for parcels, messages and like articles, which comprises a track, a plurality of carriers to travel along said track, means to unload any one of said carriers at any one of a plurality of stations along said track, and jointly acting means to control said unloading means including a device adapted to be manually set to ultimately cause the unloading of a carrier at a given one of said stations, co-acting mechanism controlled by the first of said carriers to pass a given point in said track, and a carrier controlling time-element device having a time measuring part movable in close correspondence with the movement of a loaded carrier and started into operation by said passage of said carrier past said given point, said devices and mechanism having operative connections therebetween whereby while the setting of said first mentioned device predetermines the station at which a carrier is to unload, the passage of a carrier past said given point is requisite to render operative said means to control said unloading means, and said time-element device of itself determines the station at which said loaded carrier is unloaded.

51. A delivery system for parcels, messages and like articles, which comprises a track, a plurality of carriers to travel along said track, means to unload any one of said carriers at any one of a plurality of stations along said track, and conjointly acting means to control said unloading means including a device adapted to be manually set to ultimately cause the unloading of a carrier at a given one of said stations, a second device controlled by the first of said carriers to pass a given point in said track, a time-element mechanism jointly controlled by said first and second devices and operative connections between said devices and time-element mechanism whereby while the setting of said first device predetermines the station at which a carrier is to unload, the

passage of a carrier past said given point is requisite to render operative said time-element mechanism to time said last mentioned carrier, said time-element mechanism being distinct from said carrier.

52. A delivery system comprising a way, a plurality of carriers to travel along said way, said way having therealong a station at which a load is emplaced on any one of said carriers, and a plurality of other stations at each of which said load may be deposited, carrier unloading means a part of which is at each of said other stations, controlling and timing mechanism for said carrier unloading means to only render operative the said part for a predetermined one of said other stations, a substantially determined period of time after said carrier has passed all stations which may lie along its path of travel toward the station at which said load is to be deposited, and means to actuate said timing mechanism during the whole of said period of time.

53. A delivery system comprising a way, a plurality of carriers to travel along said way, said way having therealong a station at which a load is emplaced on any one of said carriers, and a plurality of other stations at each of which said load may be deposited, carrier unloading means a part of which is at each of said other stations, controlling mechanism for said carrier unloading means to only render operative the said part for a predetermined one of said other stations, a substantially determined period of time after said carrier has been loaded at said first mentioned station, and means to actuate said controlling mechanism during substantially the whole of said period of time.

54. A delivery system comprising a way, a plurality of carriers to travel along said way, said way having therealong a station at which a load is emplaced on any one of said carriers and a plurality of other stations at each of which said load may be deposited, carrier unloading means, a part at least of which travels with each of said carriers, controlling mechanism for said parts to only actuate the said part for a predetermined one of said carriers, a substantially determined period of time after said carrier has passed all stations which may lie along its path of travel toward the station at which said load is to be deposited, and means to actuate said controlling mechanism during substantially the whole of said period of time.

55. A pick-up carrier system comprising a way having therealong a plurality of stations, carriers to travel along said way and having parts adapted to pick up a load at any predetermined one of said stations, and means for predetermining the station at which said load is to be picked up, said

means including a device at each of said stations for actuating a pick-up part of any one of said carriers, said devices being normally out of the path of said carriers, elements also normally out of the path of said carriers and each adapted when in said path to effect an engagement between the pick-up part of any carrier which passes said element and the next pick-up actuating device which said carrier passes, and means, at a point remote from the station at which the load is to be picked up, for controlling the movement into the path of the carriers of the one of said elements at the station at which the load is to be picked up.

56. A pick-up system for parcels, messages and like articles, which comprises a track having therealong a plurality of stations, means for holding an article to be despatched at at least one of said stations, a pick up carrier to travel along said track from said holding means toward said other stations, means to propel said carrier along said track, means to actuate parts of said carrier to pick up an article from said holding means as said carrier passes the same, and means to actuate parts of said carrier

to deposit said article at any predetermined one of said other stations, said last mentioned means including an electrically conductive operating part, a time-element mechanism adapted to be set to run for a determined period in substantial synchronism with the period during which said carrier is traveling from said holding means toward said operating part and means controlled by said time-element mechanism for electrically energizing said operative part.

57. A delivery system comprising a way having stations therealong, a plurality of carriers to travel along said way, means for automatically loading said carriers, means at one of said stations for determining which of said carriers shall be automatically loaded by said loading means at another of said stations, and means for automatically unloading said loaded carrier.

In testimony whereof I have affixed my signature, in the presence of two witnesses.

JAMES T. COWLEY.

C. L. JENNINGS,
T. M. LEE.

Copies of this patent may be obtained for five cents each, by addressing the "Commissioner of Patents,
Washington, D. C."

It is hereby certified that in Letters Patent No. 1,170,048, granted February 1, 1916, upon the application of James T. Cowley, of North Scituate, Massachusetts, for an improvement in "Distributing Systems," an error appears in the printed specification requiring correction as follows: Page 8, claim 12, strike out line 94 and insert the words and commas *way, means, separate from the carrier, to;* and that the said Letters Patent should be read with this correction therein that the same may conform to the record of the case in the Patent Office.

Signed and sealed this 30th day of January, A. D., 1917.

[SEAL.]

F. W. H. CLAY,
Acting Commissioner of Patents.
